UNITED STATES PATENT OFFICE

DON G. ELLIS, OF DETROIT, MICHIGAN, ASSIGNOR TO KELVINATOR CORPORATION, OF DETROIT, MICHIGAN, A CORPORATION OF MICHIGAN

EVAPORATOR

Application filed March 21, 1928. Serial No. 263,563.

This invention relates to mechanical refrigerating apparatus, and more particularly to evaporators.

An object of my invention is to increase the efficiency of refrigerating systems of the flooded type by providing the evaporator with means for conducting the gasified refrigerant from the vapor space at a point remote from the vertical plane of the refrigerant inlet.

Another object of the invention is to provide an evaporator with detachable means through which gasified refrigerant is conducted from the interior thereof to an exterior return conduit.

These and other objects will appear more in detail in the following description of an embodiment of my invention.

In the accompanying drawings:
20 Fig. 1 is a side elevational view partially in section illustrating an evaporator incorporating an embodiment of my invention;

Fig. 2 is a fragmentary end elevational view of the same; and

25 Fig. 3 is a sectional view of the evaporator taken on line A—A of Fig. 1.

Referring now to the drawings by characters of reference, 10 represents a vessel or header adapted to contain a body of liquid refrigerant and oil in solution. The header is preferably formed of a cylindrical shell which is provided at one end with a permanently attached closure 11 and at the other end with a detachable closure plate 12, the plate 12 being secured by the detachable screws 13 to the ring 9 which is secured to the end of the shell. A plurality of depending pipe loops 14 form a part of the evaporator, the ends of the pipe loops being secured to and extending into the header in open communication with the liquid contained therein.

The detachable end closure plate 12 is provided with openings through which refrigerant enters and leaves the header, the lower opening 15 serving as the inlet while the upper opening 16 serves as the outlet. Valve mechanism 17 is carried by the removable end plate and operates automatically to control the liquid refrigerant entering the header

through the inlet opening. Such valve mechanism includes a float, the position of which controls the valve to maintain a substantially constant body of refrigerant in the header. This type of vaporizer and valve mechanism, 35 so far referred to, is of a type fully described in Patent 1,615,406 issued January 25, 1927 to J. R. Repleglo.

With structures of the character illustrated in the Repleglo patent, considerable un-gasified refrigerant enters the outlet opening, resulting in reduced efficiency. This condition results from the outlet opening being located in the same vertical plane with the inlet opening, because in such plane intense agitation takes place due to the entrance of the liquid refrigerant into the body of warmer refrigerant in the evaporator causing liquid refrigerant to be projected into the vapor space adjacent the outlet opening. In order to overcome this condition and increase the efficiency of the system, I provide an outlet tube 18 which is of a length sufficient to place the open end 19 thereof in a vertical plane which is remote from that in which the inlet opening is located. In this manner the refrigerant leaving the evaporator is taken from a point in the vapor space which contains the least moisture. The other end of the outlet tube 18 extends through the outlet opening 16 to the exterior of the header. The refrigerant, preferably SO_2 , is of greater specific gravity than the oil which travels in circuit therewith, and the liquid in the header will separate into two layers, the upper layer 20 containing a greater amount of oil than the lower layer 21. The tube 18 is provided with an opening 22 adjacent the constantly maintained upper level of the liquid in the header, so that oil will drain by gravity into the outlet tube from the upper layer and will thus automatically maintain a constant quantity of oil in the header.

The outlet tube is arranged and secured so that it can be readily and separately removed from the header. The end of the tube projecting exteriorly of the end closure plate has integrally secured thereto a flange 23 which interfits with and seals against a complementary surface formed on the removable end 100

plate. A fitting 24 interfits with the outer end of the flange 23 and detachable studs 25 are utilized to secure the fitting and the flange to the end plate. A refrigerant return conduit 26 is attached to the fitting 25, and a refrigerant feed conduit 27 is secured to a fitting 28 which is screwed into the inlet opening 15 in the removable end closure plate. By removing the studs 25, the fitting and flange can be detached from the end plate, and the outlet tube 18 can be pulled through the outlet opening in the removable end plate. With this construction the outlet tube can be readily removed and inserted without removing the end plate or disturbing the valve mechanism.

Various changes can be made in the details of construction described without departing from the spirit of my invention or the scope of what is claimed.

What I claim is:—

1. In a mechanical refrigerating system, a refrigerant evaporator provided with a head having refrigerant inlet and outlet openings formed therein, a float valve mechanism for controlling the admission of refrigerant liquid through said inlet opening, a flange collar disposed externally of the head adjacent the outlet opening, a refrigerant fluid outlet tube secured at one end in the flange collar and projecting through the outlet opening formed in the head into the interior of the evaporator, and means for securing the flange collar rigidly to the head.
2. In a mechanical refrigerating system, a refrigerant evaporator provided with a head having inlet and outlet openings formed therein, means associated with the inlet opening for admitting a predetermined quantity of refrigerant liquid to the evaporator, and a refrigerant fluid outlet tube detachably secured externally of the evaporator and projecting through the aforesaid outlet opening into the interior thereof.
3. In a mechanical refrigerating system an evaporator having a removable head provided with refrigerant inlet and outlet openings, means for maintaining a relatively constant level of liquid refrigerant therein, and a removable outlet tube projecting into the evaporator through the outlet opening, said tube having an opening therein remote from the removable head and in a plane above the level of the liquid refrigerant.
5. In testimony whereof I have affixed my signature.

DON G. ELLIS.
